**NAIL CLIPPER ATTACHMENT TO RECEIVE
 THE CUT CLIPPINGS**
 Perry J. Chase, Columbus, Ohio
 (1815 Blake Blvd. SE., Cedar Rapids, Iowa)
 Filed Feb. 26, 1964, Ser. No. 347,557
 1 Claim. (Cl. 30—124)

This invention relates, in general, to nail clippers designed for manicuring. It relates, more specifically, to a novel nail clipping retainer or receptacle attachment for utilization with the pincers type nail clippers having a pair of opposed, relatively movable spring arms.

Nail clippers of this type are provided with opposed cutting edges formed at the ends of each spring arm and are operated by pressing the arms together between the fingers. The nail clippings thus cut off are usually forcefully propelled from between the spring arms and away from the cutting edges as a result of the pinching method of operation. This results in the loss of the nail clippings which are then undesirably scattered in a relatively wide area on the floor, rugs, and on a person's clothing. In attempting to eliminate this problem, nail clippers of this type have been structurally modified to incorporate nail clipping retainers or receptacles. Such prior art devices as have been devised have not been found to be completely satisfactory in that the manufacturing costs are undesirably increased where the clipper structure is modified. Further, the prior art devices were not effective in capturing the nail clippings which were ejected laterally from the clipper. Also, the structural modifications that were made often increased the size of the clipper thereby detracting from the compactness.

It is therefore, the primary object of this invention to provide a nail clipping receptacle which is attachable to a nail clipper for collecting and retaining the nail clippings.

It is another object of this invention to provide a nail clipping receptacle attachment for nail clippers of the spring arm type which receptacle is of wedge-shape for positioning between the arms.

It is a further object of this invention to provide a nail clipping receptacle attachment for nail clippers of the spring arm type which is formed from a flexible, resilient material to facilitate positioning the opening thereof closely adjacent to the nail cutting edges to prevent the escape of nail clippings.

It is also an object of this invention to provide a nail clipping receptacle for nail clippers of the spring arm type and which is of simple construction and may be economically fabricated and readily attached to nail clippers of the present construction.

These and other objects and advantages of the present invention will be readily apparent from the following detailed description of an embodiment thereof and the accompanying drawings.

In the drawings:

FIGURE 1 is a perspective view of a spring arm type nail clipper for manicuring having a nail clipping receptacle embodying this invention attached thereto.

FIGURE 2 is a perspective view of the nail clipping receptacle.

FIGURE 3 is a top plan view, on an enlarged scale, of the nail clipper of FIGURE 1.

FIGURE 4 is a longitudinal sectional view taken along line 4—4 of FIG. 3 but with the cutting edges in engagement.

FIGURE 5 is a transverse sectional view taken along line 5—5 of FIG. 4.

FIGURE 6 is an end view of the nail clipping receptacle as normally expanded.

Having reference to the drawings illustrating a nail clipper designed for manicuring purposes and the nail clipping receptacle of this invention, the numeral 10 designates, in general, the nail clipper. This nail clipper

10 is of the usual form and construction, having a pair of elongated spring arms or jaw members 11 and 12 which are welded or otherwise rigidly secured together at one end. The spring arms 11 and 12 are relatively divergent with the ends opposite their riveted juncture being normally spaced apart although they may be pressed together in opposition to their inherent resilient force. Formed at the free end of each arm, 11 and 12, and extending transversely thereto, is an inturned lip or flange, 13 and 14, with the opposed edges thereof being provided with cooperatively engageable cutting edges. Preferably, the flanges 13 and 14 and their associated cutting edges are arcuately curved to facilitate cutting of the curved nail edge.

Actuation of the spring arms 11 and 12 to perform a cutting operation is by means of a cam lever 15 pivoted at one end to a pin 16. The pin 16 extends through aligned openings formed in the arms 11 and 12 adjacent the flanged ends and in which it is rotatably mounted. An enlarged head 17 is formed on the end of the pin 16 opposite the end to which the lever 15 is attached and which, in cooperation with the lever, retains the pin in position. Formed in the pin 16 adjacent the end opposite the head 17 is a hook 18 for pivotally engaging the loop 19 formed in the end of the lever 15. A fulcrum 20, consisting of a barb struck out from the body of the lever 15 adjacent the loop 19, is also provided to further facilitate the operation of the clipper.

The clipper 10 is assembled to normally space apart the cutting edges of the flanges 13 and 14 a distance substantially greater than the thickness of the finger nails with the resiliency of the arms 11 and 12 maintaining the open spacing. For utilization, the lever 15 will be positioned as illustrated in FIGS. 1 and 4 and the lever pivoted toward the arms. This pivoting movement will cause the cutting edges to close, as indicated in FIG. 4, and clip the nail. The portion of the nail thus removed, the nail clipping, is advantageously received and retained by the novel nail clipping receptacle, designated generally by the numeral 25, provided by this invention.

45 The nail clipping receptacle 25 is of a general overall shape similar to the general form of the clipper 10 and is disposed between the arms 11 and 12. It is of hollow form with a closed transverse cross section and is provided with an open end which is positioned adjacent the flanges 13 and 14 for receiving the nail clippings as they are removed and to permit discharge of an accumulation of nail clippings, at the conclusion of the manicure, into a suitable disposal container.

Being disposed between the spring arms 11 and 12, the receptacle 25 is wedge shaped, having opposed side walls 26 extending substantially along the longitudinal edges of the arms and opposed top and bottom walls 27 which interconnect with the side walls. Since the spring arms 11 and 12 are divergent, each side wall 26 is triangularly shaped with the base thereof disposed adjacent the flanges 13 and 14 of the spring arms and their respective cutting edges. The top and bottom walls 27 accordingly converge from the open mouth end of the receptacle toward the opposed end thereof where they are joined as at 28. The edges 29 of the top and bottom walls 27 forming the receptacle opening are preferably curved with the width of such walls adjacent the cutting edge flanges being slightly greater than the width of the spring arms 11 and 12 in this area, as best shown in FIGS. 3 and 6, to form a forwardly projecting lip 30 with the marginal ends of the side walls 26. The lips 30 extend forwardly to

substantially enclose the sides of the flanged cutting edges and thereby prevent escape laterally of the nail clippings after they are cut. Both walls 27 are formed with a relatively convex curvature or outward bow with the spacing of the walls being sufficient to form an opening slightly greater than the normal spacing between the cutting edges of the flanges 11 and 12 and, preferably, position the walls 27, at their greatest spacing, adjacent the opposed surfaces of the spring arms 11 and 12.

In accordance with this invention, the receptacle 25 is fabricated from a resilient, flexible material to permit closing of the cutting edges through the normal flexing of the spring arms 11 and 12. The material utilized may be any of the well-known thermo-setting synthetic resins having the desired characteristics of flexibility and resilience. With the actuating lever 15 placed in the operating position and the spring arms 11 and 12 flexed normally open, the receptacle 25 will have a cross-sectional shape substantially as shown in FIG. 6 due to the curvature of the top and bottom walls 27. Subsequent closing of the cutting edges will compress the walls 27 together and the cross-sectional shape will be distorted as is best shown in FIG. 5. The walls 27 will thus become substantially parallel and, as a result, the side walls 26 will be further separated. Forming the walls 27 with a curvature in this manner permits the receptacle to have a relatively large opening when the clipper is in a normally open configuration thereby facilitating entry of the fingernail and readily accommodates the distortion resulting from closing the cutting edges. The flexure of the opposed walls 27 inwardly of the receptacle results in further bending along the juncture of these walls with the walls 26 where it will not adversely affect the structure of the receptacle.

Maintenance of the receptacle 25 in the desired relationship to the nail clipper 10 is accomplished by means of engagement of the receptacle with the pin 16 and the edges 29 engaging the inner surfaces of the flanges 11 and 12. Formed in the marginal edge portion of each wall 27 is a key-slot which is engageable with the pin 16. Each key-slot includes a circular portion 31 spaced a distance inwardly of the edge 29 and a slot 32 opening from the circular portion to the edge. The circular portion 31 is of a diameter slightly greater than the pin 16 while the width of the slot 32 is substantially less. Thus, the pin 16 may rotate within the circular portion 31 as is necessary when pivoting the lever 15 and pin 16 between the carrying and operating positions. Attachment or removal of the receptacle 25 may be accomplished by forcibly passing the pin 16 through the slot 32. By appropriately locating the circular portion 32 relative to the edge 29 in relationship to the spacing of the pin 16 relative to the flanges 11 and 12, it will be seen that the receptacle 25 will not be able to rotate about the pin and will always be maintained in the proper position for receiving the nail clippings. The edges 29 of the walls 27 will engage the inwardly facing surfaces of the flanges 11 and 12 and thereby prevent the undesirable pivoting of the receptacle.

Removal of the nail clippings accumulated within the receptacle 25 is a relatively simple operation. The nail clipper is merely held over a suitable waste container with the open end of the receptacle directed downwardly and shaken to dislodge the clippings.

It will be readily apparent that a nail clipper provided with a nail clipping receptacle of this invention is of particular advantage in that all of the nail clippings will be received therein. The receptacle is contained sub-

stantially within the usual nail clipper constructions and thereby avoids the addition of any undesirable bulk to the clipper. It is a compact unit that may be readily attached to the present commercially available clippers and which may be economically manufactured.

According to the provisions of the patent statutes, the principles of this invention have been explained and have been illustrated and described in what is now considered to represent the best embodiment. However, it is to be understood that, within the scope of the appended claims, the invention may be practiced otherwise than as specifically illustrated and described.

Having thus described this invention, what is claimed is:

- 15 In combination with a nail clipper having a pair of elongated arms secured together at one of their ends and with their other ends normally resiliently held apart so that the arms are normally in diverging relationship, a cam lever carried by a pin extending between the diverging ends of said arms for moving the diverging ends relatively toward each other, said arms having at their diverging ends transversely extending but inwardly curved cutting flanges directed toward each other which are normally spaced apart but which are movable into cooperation when said diverging ends are moved toward each other, a nail clipping receptacle of generally wedge-shaped hollow form positioned between said arms and being of closed transverse cross section with a pair of divergent opposed top and bottom walls adjacent the arms and a pair of opposed side walls joining the top and bottom walls, said receptacle having a closed, tapered bottom end where all of said walls meet and an open mouth end adjacent the diverging ends of the arms and the cutting flanges thereon, said receptacle being formed 20 from a resilient material to permit flexing of the side walls as the arms are moved relatively toward and away from each other, each of said top and bottom walls being normally bowed outwardly in a transverse direction so as to frictionally engage the adjacent arm and having an outer edge which is curved inwardly and located inwardly of the corresponding inwardly curved cutting flange, each of said opposed top and bottom walls having an aperture formed therein to receive said pin with the apertures in the opposed walls being in alignment and each being of 25 keyhole form with an inner circular portion of greater diameter than said pin spaced from said outer edge and an outer communicating slot portion extending to said edge and being of less width than the diameter of said pin, said side walls having at said mouth end of the receptacle lips which extend outwardly beyond said curved edges of the opposed top and bottom walls and said curved cutting flanges to prevent the nail clippings from being propelled out of the mouth end of said receptacle as they are produced by cooperation of said cutting flanges.
